(57) **CLAIM**

The ornamental design for an “office machine with scanner,” as shown and described.

DESCRIPTION

FIG. 1 is a first perspective view of an office machine with scanner, showing our new design with a first environment; FIG. 2 is a second perspective view of FIG. 1;

FIG. 3 is a third perspective view of FIG. 1;

FIG. 4 is a fourth perspective view of FIG. 1;

FIG. 5 is an enlarged, fragmentary view of FIG. 4;

FIG. 6 is a front elevational view of FIG. 1;
FIG. 7 is a rear elevational view of FIG. 1;
FIG. 8 is a left side elevational view of FIG. 1;
FIG. 9 is a right side elevational view of FIG. 1;
FIG. 10 is a top plan view of FIG. 1;
FIG. 11 is a bottom plan view of FIG. 1;
FIG. 12 is a cross-sectional view taken along line A-A of FIG. 6;
FIG. 13 is a cross-sectional view taken along line B-B of FIG. 9;
FIG. 14 is a first perspective view of an office machine with scanner, showing our new design with a second environment thereof;
FIG. 15 is a second perspective view of FIG. 14;
FIG. 16 is a third perspective view of FIG. 14;
FIG. 17 is a fourth perspective view of FIG. 14;
FIG. 18 is an enlarged, fragmentary view of FIG. 17;
FIG. 19 is a front elevational view of FIG. 14;
FIG. 20 is a rear elevational view of FIG. 14;
FIG. 21 is a left side elevational view of FIG. 14;
FIG. 22 is a right side elevational view of FIG. 14;
FIG. 23 is a top plan view of FIG. 14;
FIG. 24 is a bottom plan view of FIG. 14;
FIG. 25 is a cross-sectional view taken along line C-C of FIG. 19;
FIG. 26 is a cross-sectional view taken along line D-D of FIG. 22;
FIG. 27 is a first perspective view of an office machine with scanner, showing our new design with a third environment thereof;
FIG. 28 is a second perspective view of FIG. 27;
FIG. 29 is a third perspective view of FIG. 27;
FIG. 30 is a fourth perspective view of FIG. 27;
FIG. 31 is an enlarged, fragmentary view of FIG. 30;
FIG. 32 is a front elevational view of FIG. 27;
FIG. 33 is a rear elevational view of FIG. 27;
FIG. 34 is a left side elevational view of FIG. 27;
FIG. 35 is a right side elevational view of FIG. 27;
FIG. 36 is a top plan view of FIG. 27;
FIG. 37 is a bottom plan view of FIG. 27;
FIG. 38 is a cross-sectional view taken along line E-E of FIG. 32; and,
FIG. 39 is a cross-sectional view taken along line F-F of FIG. 35.

(Continued)

The broken lines shown in the figures are for the purpose of illustrating environment and form no part of the claimed design.
